W. M. SAUNDERS.

PROPEL PENCIL.

APPLICATION FILED JULY 21, 1920.

1,380,743.

Patented June 7, 1921.

UNITED STATES PATENT OFFICE.

WILLIAM M. SAUNDERS, OF WATERBURY, CONNECTICUT, ASSIGNOR TO THE HOGE MANUFACTURING COMPANY, OF NEW YORK, N. Y., A CORPORATION OF NEW YORK.

PROPEL-PENCIL.

1,380,743.

Specification of Letters Patent. Patented June 7, 1921.

Application filed July 21, 1920. Serial No. 397,944.

To all whom it may concern:

Be it known that I, WILLIAM M. SAUNDERS, a citizen of the United States, residing at Waterbury, county of New Haven, 5 State of Connecticut, have invented a certain new and useful Improvement in Propel-Pencils, of which the following is a full, clear, and exact description.

My invention relates to improvements in 10 propel pencils and has for one of its objects to provide a new and improved rear-feed-propel pencil in which the lead can be inserted from the rear without removing the follower.

15 It further has for its object to provide a new and improved yielding helical thread for a propel pencil such that when the follower reaches the limit of its travel its movement of revolution is not checked.

20 It further has for its object to provide a new and improved follower and new and improved means for holding the movable parts within the pencil.

The following is a description of the embodiment of my invention reference being 25 had to the drawings in which—

Figure 1 is a longitudinal section of the pencil on a plane passing through its axis;

30 Fig. 2 is a partial longitudinal section on a plane at right angles with the sectional plane of Fig. 1;

Fig. 3 is a detail showing one end of the helix and support therefor;

Fig. 4 is a section on the line 4, 4, Fig. 1;

35 Fig. 5 is a section on the line 5, 5, Fig. 1;

Fig. 6 is a section on the line 6, 6, Fig. 2;

Figs. 7 and 8 are sectional and end views of the closure for the lower end of the magazine;

40 Figs. 9 and 10 are side elevations and end views of the follower;

Fig. 11 is a detailed side elevation of the lead and follower guide within the magazine;

45 Figs. 12 and 13 are a side elevation and end view of a follower guide within the helix, and

Fig. 14 is a perspective view of the lead carrier.

50 Referring more particularly to the drawings, 1 is a tubular pencil casing having a tapered portion 2, and 3 and 4 are ring bushings having a drive-fit in the casing 1. Between these two bushings 3 and 4, there is a

sectional tubing made up of parts 5, 6 and 7, 55 within which there is a spring helix 8. This spring helix has one or two of its central portions soldered to the portion 5, the remaining parts of the helix being free to move relatively to the portion 5 and to the 60 portions 6 and 7. The tubular portion 5 has a drive-fit in the casing 1. The result of this construction is that the helix is retained definitely fixed within the casing 1 and both of its ends can be moved longitudinally for 65 the purpose hereinafter described.

Within the helix and engaging the threads thereof is a screwthreaded plug 9 (see Fig. 9) having a hollow bore in which the lower and outwardly turned ends of a follower 10 70 are located. These outwardly turned ends of the follower engage radial holes in the plug 9 so that the follower is positively secured to that plug so as to move therewith. Abutting against the bushing 3 and extending through the bushing 4 so as to freely turn therein, is a follower guide 11 having longitudinal recesses 12. The upper end of this follower guide abuts against an internal flange formed within the plug 13. 75

This plug constitutes a closure for the lower end of the magazine 14 which is secured thereto by having its lower end crimped as at 15. The follower extends through openings 16 in this plug and its legs lie in two 80 opposite grooves 12 so as to be guided thereby. The axial position of the guide 11 with relation to the plug 13 is determined by the engagement of the follower legs with the groove 12 at the upper end of the guide, the 90

guide being thus compelled to revolve with the plug 13. This guide reinforces the lower portion of the legs of the follower 10 when the follower is nearly or fully in its downward position so as to relieve the follower 95 from twisting strain. The upper end of the follower lies in an opening 17, in a guide 18, located within the magazine 14. This guide 18 is formed from a tubular sheet of metal and is bent into the form of a cross, the two 100 arms of which are bent so as to have the faces of the metal close together, while the faces of the metal on the other two arms are spaced away so as to form the opening 17 referred to. The wire of these two followers is made of spring wire of a diameter slightly 105 smaller than the lead. The folding of the guide 18 results in the production of a cen-

tral channel which receives and guides the lead so as to prevent its moving out of alinement with the axis of the carrier 22. This cross shape guide makes a tight fit within 5 the magazine 14 so as to be held therein by friction. The edges of the walls of the opening 17 are provided with slight indentations 18 which act to assist in guiding the follower 10. This cross shape guide is provided 10 with two projections 19 upon its upper end which are spaced apart and bent over so as to cover the opening 17. They are also provided with stiffening ridges 20. In the walls of the opening 17, which are 15 opposite the two projections 19, there are slots 21, 21, as shown in Fig. 11, which permit the members of the follower 10 to be bent to one side, as shown in Fig. 2. The magazine turns freely within the casing 1 20 and is held in place by means of the lead carrier 22, which is soldered at 23 to the bushing 3. This lead carrier has an expanded end 24 which fits in the reamed portion 25 of the member 13, as shown in Fig. 25 1; the member 13 being free to turn relatively to the member 22. The expanded head has a conical member which acts to direct a lead toward the axis of the carrier.

The point of the pencil is provided with a 30 spring clutch member 25, 26, which fits on the lower end of the lead carrier 22 and yieldingly engages the lead 27 so as to prevent it from falling out of the point of the pencil. 27 is the ordinary cap which fits 35 upon the end of the magazine. The exposed end of the magazine is provided with a slot 28 in which a projection 29 extends so as to prevent the cap portion turning on the magazine. 30 is an ordinary pencil clip 40 secured to casing 1.

In assembling the pencil, the parts within the casing; namely, beginning with the part 26 and ending with the part 14, are with the exception, preferably, of the lead guide 8, 45 externally assembled, the lead carrier 22 being soldered to the bushing 23. These parts are then inserted into the casing, the fit between the casing and the parts 3, 8 and 1 being, as already stated, a drive-fit. The 50 follower is then retracted and the guide 18 forced into place within the magazine 14, the opening 17 passing over the follower 10. The cap 27 is then applied producing the completed pencil.

55 It is to be noted that there are always two complete leads and part of a third in the pencil, as indicated in Fig. 1. When the lead nearest the point is used up, the magazine is turned resulting in the retraction of 60 the follower and the plug 9 until the plug reaches its uppermost or rear position. When this takes place, the upper end of the follower has engaged the cam portions 19 of the guide 18 so as to flex the head of the 65 follower to one side out of alinement with

the axis of the lead carrier, as indicated in Figs. 2 and 6. A lead is then inserted in the guide 18 in line with the axis of the carrier 22 and the other leads and the magazine are turned so as to move the follower toward 70 the point of the pencil propelling the recently inserted lead and also the other leads which are already in the pencil. The reserve leads are kept in the spaces formed by the cross-shaped guide 18 within the magazine 14. When the follower has been moved to its extreme position toward the point of the pencil, the revolution of the magazine in the same direction will cause the plug 9 to continue to revolve with the effect of moving 75 the lower end of the spring 8 to the right (Fig. 2) until that lower end is compressed so as to be freed from the screwthreads of the plug 9. The result of this is that the magazine 14 and plug 9 can be turned indefinitely without injury to the pencil. When the motion of the plug 9 is reversed, the screwthread on the plug engages the end 80 of the spiral spring permitting it to expand and operate to propel the plug 9 with the 85 follower 10 to the right.

In a similar manner, if, after the plug 9 reaches its uppermost position, as shown in Fig. 2, the movement or revolution of the magazine 14 is continued, the upper end of the spring 8 will be compressed so that its upper end moves downward or toward the left (Fig. 2) with a similar result. On account of this feature, the pencil cannot be 90 injured by having a strain of revolution put upon the magazine 14 after the plug 9 has reached the end of its travel.

On account of the flexing of the follower, as shown in Fig. 2, by means of the cam portions 19, new leads can be supplied to the pencil without removing the follower or other internal parts, the attaining of which 100 is the principal object of my invention.

The compression and expansion of the spring when rotary movement is continued after it reaches its lower limit causes an 110 audible click which indicates that a new lead is needed. In a similar manner an audible signal is produced which indicates when the follower is fully retracted so as to 115 be in a position to permit the insertion of a new lead.

As will be obvious to those skilled in the art, my invention permits of various modifications without departing from the spirit 120 thereof or the scope of the appended claims.

What I claim is:—

1. In a propel pencil, the combination of 125 a casing having an internal screw-thread, a lead carrying tube, an externally screw-threaded plug engaging said internal screw-threads, a follower secured to said plug and having a portion normally in line with the bore thereof, a magazine having an opening in line with the axis of said plug, and means 130

for deflecting said follower out of alinement with said axis when said follower is fully retracted.

2. In a propel pencil, the combination of a casing having an internal screw-thread, a lead carrying tube, an externally screw-threaded plug engaging said internal screw-threads, a follower secured to said plug and having a portion normally in line with the bore thereof, a magazine having an opening in line with the axis of said plug, and means for deflecting said follower out of alinement with said axis when said follower is fully retracted, said follower being in the form of a hairpin and having its legs secured to said plug on opposite sides of its axis.

3. In a propel pencil, the combination of a casing having an internal screw-thread, a lead carrying tube, an externally screw-threaded plug engaging said internal screw-threads, a follower secured to said plug and having a portion normally in line with the bore thereof, a magazine having an opening in line with the axis of said plug, means for deflecting said follower out of alinement with said axis when said follower is fully retracted, said follower being in the form of a hairpin and having its legs secured to said plug on opposite sides of its axis, and a guide having longitudinal guide grooves for said follower legs extending through said plug to the bottom of said magazine.

4. In a propel pencil, the combination of a casing having an internal screw-thread, a lead carrying tube, an externally screw-threaded plug engaging said internal screw-threads, a follower secured to said plug and having a portion normally in line with the bore thereof, a magazine having an opening in line with the axis of said plug, and a core within said magazine having an opening in line with said lead carrying tube and provided at its rear ends with a cam engaged by the rear end of said follower when fully retracted so as to deflect said rear end.

5. In a propel pencil, the combination of a casing having an internal screw-thread, a lead carrying tube, an externally screw-threaded plug engaging said internal screw-threads, a follower secured to said plug and having a portion normally in line with the bore thereof, a magazine having an opening in line with the axis of said plug, said follower being in the form of a hairpin and having its legs secured to said plug on opposite sides of its axis, a core within said magazine having an elongated opening adapted to receive said hairpin follower and whose axis is in line with the axis of said lead carrying tube, the rear end of said core having a cam engaged by the rear end of said hairpin follower when fully retracted so as to be deflected by said rear end out of alinement with said opening.

6. In a propel pencil, the combination of

a casing, a spring helix therein having a turn in its central portion fixed relatively to said casing and its lower end free, a follower having a portion within said helix engaging the same and adapted to compress said free end when rotation is continued after the lower limit of the follower movement is reached, and means for rotating said follower relatively to said helix.

7. In a propel pencil, the combination of a casing, a spring helix therein having a turn in its central portion fixed relatively to said casing and its ends free, a follower having a portion within said helix and engaging the same and adapted to compress said free ends when rotation is continued after either limit of the follower movement is reached, and means for rotating said follower relatively to said helix.

8. In a propel pencil, the combination of a casing, a spring helix therein having a turn in its central portion fixed relatively to said casing and its ends free, a follower having a portion within said helix and engaging the same and adapted to compress said free ends when rotation is continued after either limit of the follower is reached, and a tube surrounding said helix, to which said helices are secured, said tube having a drive-fit in said casing, and means for rotating said follower relatively to said helix.

9. In a propel pencil, the combination of a casing, a spring helix therein having a turn in its central portion fixed relatively to said casing and its ends free, a follower having a portion within said helix and engaging the same and adapted to compress said free ends when rotation is continued after either limit of the follower is reached, a tube surrounding said helix, to which said helices are secured, said tube having a drive fit in said casing, and a sectional tube surrounding the free ends of said helix, and means for rotating said follower relatively to said helix.

10. In a propel pencil, the combination of a casing having a tapered end, a magazine rotating therein, a helical thread in said casing, a follower engaging said helical thread and rotating within said magazine and a lead carrier extending into said magazine and having an upper enlarged end, said carrier having its lower end secured to said casing and said upper end holding the magazine within said casing.

11. In a propel pencil, the combination of a casing having a tapered end, a bushing secured in said casing adjacent to said tapered end, a magazine rotatable in said casing, a helical thread within said casing, a follower engaging said helical thread and rotating within said magazine, a lead carrier extending into said magazine and having an enlarged upper end, said carrier having its lower end secured to said bushing so

110

115

120

125

130

that its enlarged end holds said magazine within said casing.

12. In a propel pencil, the combination of a casing having a tapered end, a magazine 5 rotating therein, a helical thread in said casing, a follower engaging said helical thread and rotating with said magazine, and a lead carrier extending into said magazine and

having an enlarged head on its upper end, said carrier having its lower end secured to 10 said casing and said head holding the magazine within said casing, the bore of said lead carrier passing through said head and opening into said magazine so that leads can be inserted in said carrier through said head. 15

WILLIAM M. SAUNDERS.
